(57) **CLAIM**

I claim the ornamental design for an extendable pour spout, as shown.

DESCRIPTION

FIG. 1 is a perspective view of the extendable pour spout;
FIG. 2 is a side view of the extendable pour spout;
FIG. 3 is a further side view of the extendable pour spout with
the bellows in a collapsed condition;
FIG. 4 is a bottom view of the extendable pour spout; and,
FIG. 5 is a top view of the extendable pour spout.
